Primary Examiner — Karen S Acker(74) Attorney, Agent, or Firm — Sterne, Kessler, Goldstein & Fox P.L.L.C.(57) CLAIM

The ornamental design for a portion of a display screen with icon, as shown and described.

DESCRIPTION

The FIGURE is a front view of a portion of a display screen with icon showing my new design.

The broken lines around the FIGURE show a portion of a display screen and the boundary to the claim that form no part of the claimed design.

1 Claim, 1 Drawing Sheet(56)
